[57] ABSTRACT

An insecticidal method comprising contacting insects with an insecticidally effective amount of a compound having the formula

where R' is alkyl of not more than eight carbon atoms and R² is selected from the group consisting of hydrogen and alkyl of not more than eight carbon atoms.

3 Claims, No Drawings

INSECTICIDAL METHOD USING 3-METHYLENEDIOXY-PHENYL SUBSTITUTED RHODANINES

This application is a division of copending application Ser. No. 586,053 filed Oct. 12, 1966 and now abandoned.

This invention relates to new chemical compounds having insecticidal activity and to compositions containing such compounds.

The new compounds are rhodanine derivatives having a formula selected from the group consisting of

a)

and

b)

wherein: R is selected from the group consisting of hydrocarbyl and substituted hydrocarbyl of not more than 18 carbon atoms, wherein the hydrocarbyl is selected from the group consisting of alkyl, alkenyl, aralkyl and cycloalkyl and the substituents on the hydrocarbyl are selected from the group consisting of halo, amino, cyano and lower alkoxy; R¹ and R² are selected from the group consisting of hydrogen, hydrocarbyl and substituted hydrocarbyl of not more than 18 carbon atoms, wherein the hydrocarbyl is selected from the group consisting of alkyl, alkenyl, aralkyl and cycloalkyl and the substituents on the hydrocarbyl are selected from the group consisting of halo, amino, cyano and lower alkoxy; R³ is selected from the group consisting of hydrogen, halogen and Z—O— wherein Z is selected from the group consisting of hydrocarbyl and substituted hydrocarbyl of not more than 18 carbon atoms, wherein the hydrocarbyl is selected from the group consisting of alkyl, alkenyl, aralkyl and cycloalkyl and the substituents on the hydrocarbyl are selected from the group consisting of halo, amino, cyano and lower alkoxy; and A is alkylene of not more than four carbon atoms, provided that the oxygen atoms of the —OAO— group are attached to adjacent carbon atoms of the benzene nucleus, and that not more than two of R¹, R² and R³ are hydrogen.

The invention includes a process for the production of a rhodanine derivative as defined above, which comprises reacting a salt of a dithiocarbamic acid having a formula selected from the group consisting of

c)

and

d)

with a compound of the formula

wherein A, R, R¹, R² and R³ are as defined above, M is selected from the group consisting of hydrogen, alkali metal, ammonia and alkyl of not more than four carbon atoms, and X is selected from the group consisting of fluorine, chlorine, bromine and iodine.

The insecticidal compositions of the invention comprise one or more rhodanine derivatives of the above formula in admixture with a diluent.

In the above formulas R, R¹, R² and Z as alkyl and substituted alkyl can be for example methyl, ethyl, chloromethyl, n-propyl, isopropyl, 2-cyanopropyl, n-butyl, 2-aminobutyl, sec-butyl, isobutyl, tert-butyl, amyl, hexyl, heptyl, ethoxyhexyl, octyl, nonyl, decyl, dodecyl, tetradecyl, hexadecyl, octadecyl and the various homologues and isomers of alkyl having not more than 18 carbon atoms, as alkenyl and substituted alkenyl can be for example, vinyl, allyl, n-butenyl-1, n-butenyl-2, 3-bromobutenyl-2, n-pentenyl-2, n-hexenyl-2, 3-methoxybutenyl-2, n-heptenyl, n-decenyl, n-dodecenyl and the various homologues and isomers of alkenyl having not more than 18 carbon atoms, as cycloalkyl and substituted cycloalkyl (three to 18 carbon atoms) can be for example cyclopentyl, cyclohexyl, 4-methoxycyclohexyl, mono- and polyethylcyclohexyl, cycloheptyl, 3-chloro-cycloheptyl and the like, and as aralkyl and substituted aralkyl (seven to 18 carbon atoms) can be for example benzyl, p-aminophenylmethyl, phenylethyl, diphenylmethyl, p-chloro-phenylethyl and the like.

The above formulas R, R¹, R² and Z are preferably alkyl of not more than eight carbons.

Where R³ represents a halogen atom, it can be chlorine, bromine, fluorine or iodine. R³ is preferably chlorine or bromine.

The substituent RO is preferably in the para position relative to the position of attachment of the benzene nucleus to the nitrogen atom, and R³ is preferably in the meta position.

In the formula (b) above A can be for example methylene, ethylene, ethylidene, propylene, β -propylidene and ethyl-ethylene. Preferably both oxygen atoms of the alkylene-dioxy group —OAO— are linked to the same carbon atom of the alkylene group. Especially preferred compounds are those in which A is methylene. Preferably one of the oxygen atoms of the alkylene-dioxy group —OAO— is linked to the carbon atom of the benzene ring in the para position. The other oxygen atom in such cases is necessarily linked to a carbon atom in a meta position.

Representative examples of the new rhodanine derivatives of the invention are: 3(4'-methoxyphenyl)-5-methyl-rhodanine; 3(4'-methoxyphenyl)-5-ethylrhodanine; 3(4'-methoxy-phenyl)-5-n-propylrhodanine; 3(4'-ethoxyphenyl)-5-methylrhodanine; 3(2'-5-methylrhodanine; 3(4'-ethoxy-3'-chlorophenyl)-5-methylrhodanine; 3(4'-ethoxy-3'-bromophenyl)-5-methylrhodanine; 3(4'- β -chloroethoxyphenyl)-5-methylrhodanine; 3(4'-ethoxyphenyl)-5-ethylrhodanine; 3(4'-ethoxyphenyl)-5-n-propylrhodanine; 3(3'4'-dimethoxy-phenyl)rhodanine; 3(3'4'-dimethoxyphenyl)-5-methylrhodanine; 3(4'-n-pentyloxyphenyl)-5-methylrhodanine; 3(4'-ethoxyphenyl)-5,5-dimethylrhodanine; 3(4'-allyloxyphenyl)-5-methylrhodanine; 3(4'-cyclohexyloxyphenyl)-5-methylrhodanine; 3(4'-benzyloxy-phenyl)-5-methylrhodanine; 3(4'-ethoxyphenyl)-5-methoxymethyl-

rhodanine; 3(4'-ethoxyphenyl)-5-cyclohexylrhodanine; 3(3',4'-methylenedioxophenyl)rhodanine; 3(3'4'-methylenedioxophenyl)-5-methylrhodanine; 3(3'4'-methylenedioxophenyl)-5,5-dimethylrhodanine; 3(3',4'-ethylidenedioxophenyl)-5-ethylrhodanine; 3(4'-cetoxyphenyl)-5-methylrhodanine; 3(4'- β -aminoethoxy-phenyl)-5-ethylrhodanine; 3(4'-n-pentyloxyphenyl)-5-hexyl-rhodanine; 3(4'-n-octyloxyphenyl)-5-methylrhodanine; 3(4'-n-decyloxyphenyl)-5-ethylrhodanine; 3(4'- β -cyanopropoxy-phenyl)-5-ethylrhodanine; 3(2'-propoxyphenyl)-5-propylrhodanine; 3(3',4'-dimethoxyphenyl)-5-n-octylrhodanine; 3(4'- β -pentenoxyphenyl)-5-propylrhodanine; 3(4'- β -ethyl-hexyloxyphenyl)-5-methylrhodanine; 3(4'-methoxy-3'-ethoxy-phenyl)-5-n-propylrhodanine; 3(4'-cycloheptyloxyphenyl)-5-ethylrhodanine; 3(4'-chloromethoxyphenyl)-5-methylrhodanine; 3(4'-n-heptenoxyphenyl)-5-ethylrhodanine; 3(4',3'-dimethoxy-phenyl)-5-butylrhodanine; 3(4'-ethoxyphenyl)-5-vinylrhodanine; 3(4'- β -aminopropoxyphenyl)-5-methylrhodanine; 3(4'-methoxy-3'-cyclohexyloxyphenyl)-5-methylrhodanine; 3(4'5-phenylethylrhodanine; 3(3',4'-dimethoxyphenyl)-5,5-diethyl-rhodanine; 3(4'-n-propoxyphenyl)-5-benzylrhodanine; 3(3',4'-dipropoxophenyl)rhodanine; 3(4'-methoxyphenyl)-5-laurylrhodanine; 3(3',4'- β -propylidenedioxophenyl)-5-methyl-rhodanine.

The salt of the dithiocarbamic acid that is a starting material in the process of the invention is preferably an alkali metal or ammonium salt. Where an alkali metal salt of the dithiocarbamic acid is employed, this is usually, for economic reasons, the sodium salt, but functionally other alkali metal salts, for example the lithium or potassium salts, are quite satisfactory. The ammonium salts of the dithiocarbamic acids that can be used include the substituted ammonium salts derived from, for example, primary and secondary amines, as well as the unsubstituted ammonium salts derived from ammonia itself. The last-named are often preferred, however,

For the other reactant in the process of the invention, it is preferred to use an ester or salt of the α -haloaliphatic monocarboxylic acid. Where an ester is employed, this is preferably an ester of an alcohol containing up to four carbon atoms, especially an ethyl ester. Preferred salts are the alkali metal salts, although ammonium and amine salts can also be used. The α -halogen atom is usually chlorine or bromine, and the number of carbon atoms and their arrangement in the ester is, of course, determined by the atoms or groups R¹ and R² required in the product.

The reaction between the salt of the dithiocarbamic acid and the α -haloaliphatic monocarboxylic acid or its ester or salt occurs readily at ordinary temperatures, for example in the range 10° to 25°C., although the process can be conducted at lower or higher temperatures, for example from 0° to 50° C., if desired.

In practice, the reactants are usually brought together in a liquid medium. This can conveniently be water or a mixture of water and an inert, water-miscible organic solvent, for instance a lower alkanol, a ketone, or dioxan. For example, a solution of an ester in a water miscible organic solvent, or a solution in water of a salt of the α -haloaliphatic monocarboxylic acid can be

added to a solution or suspension of the salt of the dithiocarbamic acid in water.

An insecticidal composition of the invention can be liquid or solid, and a liquid composition can be a solution, suspension or emulsion. Often a surface active agent is present to stabilize the composition or to facilitate its application.

A composition can contain a new rhodanine derivative as the only active ingredient, or one or more other compounds having insecticidal properties can be present.

A solution of a rhodanine derivative is one in an organic solvent, for example an ester, for instance butyl acetate, a ketone, for instance methyl isobutyl ketone, a petroleum fraction, for instance white spirit, an aromatic hydrocarbon, for instance xylene or solvent naphtha, a halogenated hydrocarbon, for instance carbon tetrachloride or perchlorethylene, or some other solvent, for instance isopropyl ether or dioxan.

Such a solution can be formulated for use as an aerosol by mixing with a liquid having a boiling point below ambient temperature at atmospheric pressure for example dichlorodifluoromethane.

Where a solution contains a surface active agent, this is selected according to its solubility in the solvent but it can in general be cationic, anionic or non-ionic, anionic and non-ionic materials being generally preferred. Examples of anionic surface active agents are soaps, and the alkali metal salts, particularly the sodium salts, of long-chain alkylbenzene sulphonic acids, of long-chain alkyl sulphates and of dialkylsulphosuccinates; examples of non-ionic surface active agents are ethers and esters of polyethylene glycols, for instance the polyoxyethylene derivatives of alkylphenols and of the fatty acid mono-esters of sorbitan.

Insecticidal compositions that are suspensions can be simple ones of a rhodanine derivative in finely-divided form in an aqueous medium, stabilized if necessary by the presence of a surface active agent, for instance an anionic or nonionic agent as exemplified above.

An insecticidal composition that is an emulsion can be obtained by emulsifying a solution of a rhodanine derivative in a suitable organic solvent, generally one that is water-immiscible, with water in the presence of a surface active agent. Where the solution already contains a surface active agent as described above, an emulsion can be formed simply by mixing with water under conditions of suitable agitation. Alternatively the surface active agent can be dissolved in the water and the solution of the rhodanine derivative added subsequently.

In compositions which are solids, the rhodanine derivative is generally present in finely-divided form and the diluent is an inert powder, for instance kieselguhr, calcium carbonate, diatomaceous earth or talc. Such a solid composition may also contain a surface active agent to facilitate its application.

The rhodanine derivatives may also be incorporated in media such as paints, varnishes and polishes.

The concentration of the rhodanine derivative in a composition of the invention can vary considerably provided the required dosage (that is a lethal or toxic amount) is supplied to the pests or their environment. Where the composition is a liquid, the concentration of

the active ingredient can, for example, be from 0.001 to 10 percent by weight. For a solid composition, the lower limit of concentration is generally somewhat higher, for example 0.1 percent by weight. Concentrates in which the concentration of the rhodanine derivative may be, for example, from 10 to 50 percent by weight, and which are intended for dilution before use, are a convenient form in which the insecticides can be supplied to the user.

The invention is illustrated by the following Examples.

EXAMPLE 1

This Example describes the production of the new compound 3(4'-ethoxyphenyl)-5-methylrhodanine.

Ammonium N(4-ethoxyphenyl)dithiocarbamate, required as a starting material for the production of the rhodanine derivative, was first obtained as follows: 6 cc. of carbon disulfide were added over a period of 15 minutes to a stirred mixture of 13.7 grams of p-phenetidine, 50 cc. of ethanol and 10 cc. of concentrated ammonium hydroxide. On cooling, ammonium N(4-ethoxyphenyl) dithiocarbamate crystallized from the reaction mixture and was filtered off, washed with ethanol and dried at room temperature.

The ammonium salt thus obtained was suspended in 35 cc. of water and to the stirred suspension was added a solution of 8.9 cc. of ethyl α -chloropropionate in 55 cc. of ethanol. Stirring was continued for 6 hours, after standing for a further 40 hours, 150 cc. of water were added, thereby precipitating 11.8 grams of 3(4'-ethoxyphenyl)-5-methylrhodanine in a slightly impure form having a melting point of 134°-142° C. The product was obtained as yellow needles having a melting point of 147°-151° C., by crystallization from ethanol. (Found: C, 53.8; H, 5.1; N, 5.4; S, 23.6. $C_{12}H_{13}NO_2S_2$ requires C, 53.4; H, 4.9; N, 5.3; S, 24.0 percent).

EXAMPLE 2

This Example describes the production of 3(4'-ethoxy-phenyl)-5-ethylrhodanine.

A suspension of ammonium N(4-ethoxyphenyl)dithiocarbamate was prepared by stirring a mixture of 7 cc. of concentrated ammonium hydroxide, 13.7 grams of p-phenetidine, 9 cc. of carbon disulfide and 25 cc. of ethanol for 2 hours at 0°C. To the suspension there was then gradually added a solution of sodium α -bromobutyrate obtained from 16.7 grams of α -bromobutyric acid, 4 grams of sodium hydroxide and 30 cc. of water.

After standing overnight, the reaction mixture was acidified to pH 3 by the addition of dilute hydrochloric acid, and was then warmed to 65°C. for 2 hours. After cooling, 27.1 grams of slightly impure 3(4'-ethoxyphenyl)-5-ethylrhodanine having a melting point of 98°-100°C. were collected by filtration. Two recrystallizations from ethanol raised the melting point to 105°-106° C. (Found: C, 55.4; H, 6.4; N, 4.7; S, 20.8. $C_{13}H_{15}NO_2S_2$ requires; C, 55.6; H, 6.1; N, 4.5; S, 20.7 percent).

EXAMPLE 3

3(4'-Ethoxyphenyl)-5-n-propylrhodanine was obtained from ammonium N(4-ethoxyphenyl)dithiocar-

bamate and sodium α -bromovalerate by essentially the same procedure as that described in the previous Example using 1/10 molar quantities of reactants. The yield of the initial product was 27.5 grams, and its melting point was 100°-102° C. This was raised to 105°-106 ° C. by recrystallizing twice from ethanol. (Found: C, 57.0; H, 6.1; N, 4.9; S, 21.1. $C_{14}H_{17}NO_2S_2$ requires C, 56.9; H, 5.8; N, 4.7; S, 21.7 percent).

EXAMPLE 4

This Example describes the production of 3(4'-ethoxy-phenyl)-5,5-dimethylrhodanine.

A solution of sodium α -bromoisobutyrate, obtained from 16.7 grams of α -bromoisobutyric acid, 4 grams of sodium hydroxide and 30 cc. of water, was added gradually to a stirred suspension of ammonium N(4-ethoxyphenyl)dithiocarbamate, itself obtained by stirring a mixture of 7cc. of concentrated ammonium hydroxide, 13.7 grams of p-phenetidine, 9 cc. of carbon disulfide and 25 cc. of ethanol for 2 hours.

After standing overnight, the reaction mixture was acidified to pH 3 by the addition of dilute hydrochloric acid, and was then warmed at 65° C. for 2 hours. The main product, which was collected by filtration after cooling, was N,N-bis(4-ethoxyphenyl)thiourea. On standing, the mother liquors deposited a further crop of crystals having a melting point of 120°-122° C., which were identified as the required 3(4'-ethoxyphenyl)-5,5-dimethylrhodanine. The melting point was raised to 122°-125° C. on recrystallization from ethanol. (Found: C, 55.1; H, 5.5; N, 5.2; S, 23.0. $C_{13}H_{15}NO_2S_2$ requires C, 55.5; H, 5.4; N, 5.0; S, 22.8 percent).

EXAMPLE 5

This Example describes the production of 3(4'-n-butoxyphenyl)-5-methylrhodanine.

A solution of ammonium N(4-n-butoxyphenyl)dithiocarbamate was prepared by shaking a mixture of 16.5 grams of 4-n-butoxyaniline, 10 cc. of concentrated ammonia, 6 cc. of carbon disulfide and 30 cc. of ethanol for 2 hours and then allowing to stand at 0°-5° C. overnight. -methylrhodanine.

A half portion of this solution was then treated with a solution of 6.5 cc. of ethyl α -bromopropionate in 30 cc. of ethanol. Crystalline material precipitated almost immediately, and after some hours standing, the weight collected by filtration was 5.6 grams. The organic constituent of this material was identified as N,N'-bis(4-n-butoxyphenyl)thiourea. On further standing, the mother liquors from the filtration deposited a further crop of crystals weighing 1.4 grams. The melting point of these crystals was 87°-89° C., and analysis indicated that they were the required 3(4'-n-butoxyphenyl)-5-methylrhodamine. (Found: C, 57.2; H, 5.7; N, 4.8; S, 21.4; $C_{14}H_{17}NO_2S_2$ requires C, 56.9; H, 5.8; N, 4.7; S, 21.6 percent).

EXAMPLE 6

This Example describes the production of 3(4'-pentyl-oxyphenyl)-5-methylrhodanine.

A mixture of 9 grams of 4-pentoxyaniline, 4cc. of carbon disulfide, 20 cc. of ethanol and 4 cc. of concentrated ammonium hydroxide was stirred at 0°C. for 2 hours. Then 7 cc. of ethyl α -bromopropionate were

added to the solution thus obtained, and the reaction mixture was allowed to stand overnight. On filtering, 2.6 grams of a solid mixture of ammonium bromide and N,N'-bis(4-pentyloxyphenyl) thiourea were separated.

On further standing, the mother liquors deposited two further crops of crystals weighing respectively 2.2 grams and 2.3 grams. Recrystallization of the former from ethanol gave 1.1 grams of 3(4'-pentyloxyphenyl)-5-methylrhodanine having a melting point of 81°-83° C. (Found: C, 58.1; H, 6.4; N, 4.7; S, 20.8. $C_{15}H_{19}NO_2S_2$ requires C, 58.3; H, 6.1; N, 4.5; S, 20.7 percent). Recrystallization of the second crop from ethanol gave 1.6 grams of slightly less pure 3(4'-pentyloxyphenyl)-5-methylrhodanine having a melting point of 72°-80° C.

EXAMPLE 7

This Example describes the production of 3(4'-ethoxy-3'-chlorophenyl)-5-methylrhodanine.

A solution of 1.65 cc. of ethyl α -bromopropionate in 18.6 cc. of ethanol was added to a stirred suspension of 3.1 grams of ammonium N(4-ethoxy-3-chlorophenyl)dithiocarbamate in 12.4 cc. of water. (The ammonium salt was first obtained in an analogous manner to the ammonium N(4-ethoxyphenyl) dithiocarbamate described in Example 1).

Next day, 31 cc. of water were added, and the residual solid, which weighed 2.5 grams, was filtered off. 3(4'-Ethoxy-3'-chlorophenyl) rhodanine having a melting point of 171°-172° C. was obtained by two successive crystallizations from ethanol. (Found: C, 48.1; H, 4.1; N, 4.4; S, 20.5; Cl, 11.6; $C_{12}H_{12}Cl NO_2S_2$ requires C, 47.8; H, 4.3; N, 4.6; S, 21.2; Cl, 11.8 percent).

EXAMPLE 8

This Example describes the production of 3(3', 4'-dimethoxyphenyl)rhodanine.

A mixture of 15.3 grams of 3,4-dimethoxyaniline, 50 cc. of ethanol, 10 cc. of concentrated ammonium hydroxide solution and 6 cc. of carbon disulfide was stirred for 1 hour at 0° C. and was then allowed to stand for a further hour at the same temperature. Ammonium N(3,4-dimethoxyphenyl)dithio-carbamate crystallized out and was collected by filtration and dried.

A solution of 5.5 cc. of ethyl chloroacetate in 30 cc. of ethanol was added to a stirred suspension of 11.7 grams of the above ammonium salt in 50 cc. of water at room temperature. The product which separated was filtered off after 1 hour, boiled with 15 cc. of ethanol, cooled, and again filtered, leaving a small ethanol-insoluble residue. The ethanol extract was combined with the mother liquor from the first filtration, and this solution was then diluted with 150° C of water. Solid material contaminated with tar which separated during several days standing was collected by filtration. Stirring with fresh ethanol left 1 gram of an off-white solid having a melting point of 209°-210° C., and crystallization of the solid from a large volume of ethanol gave 3(3',4'-dimethoxyphenyl) rhodanine, melting point 215°-216° C. (Found: C, 49.3; H, 3.6; N, 5.8; S, 22.6. $C_{11}H_{11}NO_3S_2$ requires C, 49.9; H, 4.1; N, 5.2; S, 23.8 percent).

EXAMPLE 9

This Example describes the production of 3(3',4'-dimethoxyphenyl)-5-methylrhodanine.

A solution of 6.5 cc. of ethyl α -bromopropionate in 30 cc. of ethanol was added to a stirred suspension of 11.7 grams of ammonium N(3,4-dimethoxyphenyl)dithiocarbamate (prepared as described in Example 8) in 50 cc. of water. Essentially the same procedure as that described in Example 8 was followed in isolating the product. The solid obtained after stirring with fresh ethanol weighed 4.5 grams and had a melting point of 155°-157° C. Crystallization from a large volume of ethanol raised the melting point to 160°-162° C. (Found: C, 51.0; H, 4.6; N, 5.1; S, 22.3. $C_{12}H_{13}NO_3S_2$ requires C, 50.9; H, 4.6; N, 4.9; S, 22.6%).

EXAMPLE 10

This Example describes the production of (4'-n-propoxyphenyl)-5-methylrhodanine.

A mixture of 15.1 Grams of p-n-propoxyaniline, 9 cc. of carbon disulfide and 25 cc. of ethanol were stirred for 2 hours at 0° C. A solution made from 15.3 grams of α -bromo-propionic acid, 4 grams of sodium hydroxide and 30 cc. of water was added at 0° C. Next day the reaction mixture was acidified to pH 3 with hydrochloric acid and heated to 60-70° C. for 2 hours. After cooling, 38.1 grams of the crude product, which had a melting point of 112°-114° C., were filtered off and recrystallized from 320 cc. of ethanol, yielding 21 grams of 3(4'-n-propoxyphenyl)-5-methylrhodanine in the form of pale yellow needles having a melting point of 124°-126° C.

Analysis of the product gave C, 56.3 percent; H, 5.4 percent, N, 5.6 percent; $C_{13}H_{15}NO_2S_2$ required C, 55.5 percent; H, 5.3 percent, N, 5.0 percent.

EXAMPLE 11

This Example describes the production of 3(4'-isopropoxyphenyl)-5-methylrhodanine.

The method described in Example 10 was used with the substitution of p-isopropoxyaniline for p-propoxyaniline.

The yield of crude product was 28.7 grams with a melting point of 95°-97° C. This gave 24 grams of a purified product with a melting point of 103°-105° C. upon recrystallization.

Analysis of the purified product gave C, 55.5 percent; H, 5.5 percent; N, 4.8 percent; $C_{13}H_{15}NO_2S_2$ requires C, 55.5 percent; H, 5.3 percent; N, 5.0 percent.

EXAMPLE 12

This Example describes the production of 3(4'-n-hexyloxyphenyl)-5-methylrhodanine.

The method as described in Example 10 was used with the substitution of 19.3 grams of p-n-hexyloxyaniline for the p-n-propoxyaniline.

The yield was 28.7 grams of the crude product which had a melting point of 93°-94° C. Recrystallization gave 20 grams of a purified product with a melting point of 111°-113° C.

Analysis of the purified product gave C, 60.4 percent; H, 6.7 percent; N, 4.0 percent; $C_{10}H_{21}NO_2S_2$ requires C, 59.5 percent; H, 6.5 percent; N, 4.3 percent.

EXAMPLE 13

This Example describes the production of 3(4'-methoxyphenyl)-5-methylrhodanine.

The method as described in Example 10 was used, with 12.3 grams of p-anisidine substituted for the p-n-propoxyaniline.

The yield of crude product was 24.4 grams and from this 16 grams of a purified product with a melting point of 135°-137° C. were obtained by recrystallization.

Analysis of the purified product gave C, 52.6 percent; H, 4.2 percent; N, 5.2 percent; $C_{11}H_{11}NO_2S_2$ requires C, 52.2 percent; H, 4.4 percent; N, 5.5 percent.

EXAMPLE 14

This Example describes the production of 3(4'-methoxyphenyl)-5-ethylrhodanine.

The method was basically that described in Example 10 using as starting materials 12.3 grams of p-anisidine and 16 grams of α -bromobutyric acid, yielding 16.3 grams of a crude product having a melting point of 64°-65° C. This yielded 9 grams of a purified product having a melting point of 95°-96° C.

Analysis of the final product gave C, 53.8 percent; H, 4.7 percent; N, 5.1 percent; S, 23.8 percent; $C_{12}H_{13}NO_2S_2$ requires C, 53.9 percent; H, 4.9 percent; N, 5.3 percent; S, 24.0 percent.

EXAMPLE 15

This Example describes the production of 3(4'-methoxyphenyl)-5-n-propylrhodanine.

The method was basically that described in Example 10 using as starting materials 12.3 grams of p-anisidine and 18 grams of α -bromovaleric acid. The yield of crude product, (melting point 73°-95° C) was 21.5 grams, and this in turn gave 14 grams of a purified product having a melting point of 95°-97° C. on recrystallization from 70 cc. of ethanol. The further purified sample had a melting point of 96°-98° C.

Analysis gave C, 55.5 percent; H, 5.3 percent; N, 5.0 percent; S, 22.8 percent; $C_{13}H_{15}NO_2S_2$ requires C, 55.5 percent; H, 5.3 percent; N, 5.0 percent; S, 22.6 percent.

EXAMPLE 16

This Example Describes the production of 3(3',4'-methylenedioxyphenyl)-5-methylrhodanine.

The method described in Example 10 was used, with the modification that 13.7 grams of 3,4-methylenediox-*y*-aniline in 50 cc. of methanol were used in place of p-n-propoxyaniline in ethanol.

A yield of 15.9 grams of a crude product with a melting point of 162° C. was obtained. When this was slurried with hot ethanol and cooled, 13.7 grams of a purified product have a melting point of 169°-170° C. resulted. An analytical sample recrystallized from ethanol had the form of irregular cream prisms with a melting point of 170°-171° C.

Analysis of this sample gave C, 49.0 percent; H, 3.2 percent; N, 5.2 percent; $C_{11}H_8NO_3S_2$ requires C, 49.4 percent; H, 3.3 percent; N, 5.2 percent.

EXAMPLE 17

This Example describes the production of 3-(3',4'-methylenedioxyphenyl)-5,5-dimethylrhodanine.

The method was basically that described in Example 10 using as starting materials 13.7 grams of 3,4-methylene-dioxaniline and 16.7 grams of 2-bromoisobutyric acid. A crude yield of 13 grams was obtained which when boiled with 90 cc. of ethanol gave 4.2 grams of a purified product with a melting point of 150°-153° C. A further sample had a melting point of 154°-155° C.

Analysis of this product gave C, 50.9 percent; H, 4.0 percent; N, 5.1 percent; $C_{12}H_{11}NO_3S_2$ requires C, 51.2 percent; H, 3.9 percent; N, 5.0 percent.

EXAMPLE 18

15 This Example describes the production of 3(4'-n-propoxyphenyl)-5-ethylrhodanine.

The method was basically that described in Example 10 using 16.7 grams of α -bromobutyric acid in place of the α -bromopropionic acid. The crude product was boiled with 80 cc. of ethanol and cooled, giving 20.5 grams of a yellowish solid with a melting point of 117°-180° C. A further recrystallized sample of this product had the same melting point.

Analysis of the compound obtained gave C, 56.8 percent; H, 5.7 percent; N, 4.9 percent; $C_{14}H_{17}NO_2S_2$ requires C, 56.8 percent; H, 5.8 percent; N, 4.7 percent.

The method used to assess the insecticidal activity of test compounds was as follows.

30 A 0.05 cc. portion of a 1 percent by weight solution of the compound in acetone was added to 50 cc. of distilled water contained in a clean 25 × 200 mm. rimless culture tube. The tube was then stoppered with an acetone-washed rubber stopper and shaken vigorously to ensure complete mixing. Then 25 early instar yellow fever mosquito larvae (*Aedes aegypti*) were introduced into the tube. After 24 hours at room temperature, mortality observations on the larvae were taken. In certain instances the test was repeated at lower concentration of the test compound.

35 The results obtained on certain of the compounds described in the above Examples are shown in the following table:

Compound	% Mortality/Concentrations of test compound p.p.m.
50 3(4'-Ethoxyphenyl)-5-methylrhodanine	100/10
3(4'-Ethoxyphenyl)-5-ethylrhodanine	100/10 - 90/2
3(4'-Ethoxyphenyl)-5-n-propylrhodanine	100/10 - 70/2
3(4'-Pentyloxyphenyl)-5-methylrhodanine	90/10
55 3(4'-Ethoxy-3'-chlorophenyl)-5-methylrhodanine	100/10

60 In addition 3(4'-ethoxyphenyl)-5,5-dimethylrhodanine gave a 100 percent kill at 2ppm in tests on *Aedes* mosquito.

65 Besides the insecticidal activity demonstrated above, the rhodanine derivatives of the invention were also found to be active molluscicides.

Although the invention is described with respect to specific examples, it is not intended that the details thereof are limitations on the scope of the invention except to the extent incorporated in the following claims.

What is claimed is:

1. An insecticidal method comprising contacting insects with an insecticidally effective amount of a compound having the formula

wherein R¹ is alkyl of not more than eight carbon atoms and R² is selected from the group consisting of hydrogen and alkyl of not more than eight carbon atoms.

- 5 2. The method of claim 1 wherein the compound is 3-(3',4'-methylenedioxyphenyl)-5-methylrhodanine.
 3. The method of claim 1 wherein the compound is 3-(3',4'-methylenedioxyphenyl)-5,5-dimethylrhodanine.
